UNITED STATES PATENT OFFICE.

CHARLES S. PINE, OF PROVIDENCE, RHODE ISLAND.

DESIGN FOR A CHARM.

SPECIFICATION forming part of Design No. 14,549, dated January 15, 1884.
Application filed June 28, 1883. Term of patent 3½ years.

To all whom it may concern:

Be it known that I, CHARLES S. PINE, a citizen of the United States, residing at Providence, in the county of Providence and State of Rhode Island, have invented and produced a new and original Design for a Charm, of which the following is a full, clear, and exact description, reference being had to the accompanying drawings, forming part of this specification.

In the accompanying drawings, Figure 1 is a side view of my charm, such charm being used as a watch-chain pendant or ornament, which may be suspended from any other chain. Fig. 2 is a front view of the same.

The leading feature of my design consists in a disk suspended in a bifurcated arm, such disk being ornamented with radial shadings and lines extending from the center outward, and shorter lines extending from the periphery inward.

In the drawings, *a* is a ring. *b* is the bifurcated arm, in which the disk *c* is suspended. *d d* are radial shadings. *e e* are radial lines

extending from the center outward. *ff* are short lines extending from the periphery inward. By these radial shadings a brilliant effect is imparted to the disk, having the appearance of a sun. The whole presents a unique and attractive appearance.

Having thus described my invention, I claim as new and desire to secure by Letters Patent—

1. The design for a charm or pendant herein shown and described, the same consisting in a circular disk ornamented by radial lines and shadings extending from the center outward, and shorter lines extending from the periphery inward, as described. 30 35

2. The design for a charm or pendant herein shown and described, the same consisting of 40 the bifurcated arm *b* and the disk *c*, ornamented by the radial shadings *d d*, the radial lines *e e*, and the lines *ff* near the periphery, as described.
